COMBINATION SHUTTER AND AWNING

John G. Cox, Wichita Falls, Tex.

Application July 21, 1936, Serial No. 91,747

4 Claims. (Cl. 20—59)

This invention relates to improvements in a combination shutter and awning.

An object of this invention is to provide a combination shutter and awning that may be operated from the interior of the inclosure, such as a screened porch.

Another object of this invention is to provide a shutter that is weather proof when closed and may be opened to provide an awning.

10. Another object of this invention is to provide a combination awning and shutter that is inexpensive and simple to construct, easy to operate, without the necessity of the operator being exposed to the weather, and which furthermore provides a combination shutter and awning that is neat and not unsightly.

While the drawings illustrate a preferred embodiment of the invention it is to be understood that to meet specific needs and requirements, 20 changes in the minor details of construction may be resorted to within the scope of the invention as claimed without departing from the spirit thereof.

For a full understanding of the invention and 25 the merits thereof, reference is to be had to the following description and to the drawings hereto attached, in which like reference characters designate like parts in the several views.

Fig. 1 is a perspective view of the combination awning and shutter in the position to be used as 30 an awning, with parts broken away to show construction.

Fig. 2 is a side elevation of the combination shutter and awning in a closed position.

35. Fig. 3 is a section taken on the line 3—3 of Fig. 2.

Fig. 4 is a section taken on the line 4—4 of Fig. 2.

Fig. 5 is a section taken substantially on the 40 line 5—5 of Fig. 1.

Fig. 6 is a side elevation of the combination shutter and awning shown in a raised position.

Fig. 7 is an enlarged view of the guide channel and guide member.

45. Referring more particularly to the drawings, the numeral 8 indicates an upper awning frame section and 9 a lower awning frame section. 10a is a central post. 10 are posts to which weather strips 11 are attached, the weatherstrips acting

50 as guides for rollers 12 on the awning section 9. Hinges 13 connect the upper edge of the awning section to the screened porch or other inclosure and permits its upward and downward swing.

Hinges 13a are at the central joint between the 55 awning sections 8 and 9 and permit upward and

downward movement of the section 9 with section 8. Weatherstrips 14 and 14a are provided at the upper and central portions of the awning to provide weather-tight joints at these points. The awning sections are preferably covered with fabric 15, although other material may be used. A guide member 16 is hingeably secured to the lower edge of awning section 9 and is guided within a channel 20 mounted in or on post 10a. Pulleys 17 and 17a are journaled in post 10a in 10 slots extending through said post, and a looped cord 18 passes around said pulleys and is attached to lug 16a of guide member 16. By this arrangement a person may grip the portion of the cord 18 exposed on the inner side of the inclosure and lower or raise the awning to any desired position by proper manipulation of cord 18 from within the sheltered interior of the inclosure, even though screening 19 covers the opening in the inclosure between the operator and the 20 awning. A friction latch comprising members 21 and 22 attached to the post 10a and awning respectively is provided to secure the awning in a closed position so that it may serve as a shutter, as shown in Fig. 2. The latch prevents flapping 25 and banging that is usually experienced with other types of shutters.

Grooves 23 are provided in upper and lower sections 8 and 9 to interfit with weatherstrips 11, thereby forming a tight joint when the shutter 30 is closed. The lower edge of the shutter is formed by the bottom bar of the member or section 9 and is beveled to fit a correspondingly beveled edge 24 at the lower part of the opening. A frictional element 25 is provided to hold cord 18 and 35 prevent its slipping, thereby holding the awning at the desired point after it is so positioned.

In practice, the posts 10, 10a may comprise the framework or a part of the framework of a window, porch or other inclosure having an opening therein covered or not by screen material 19, and it will be seen that the invention provides a combined awning and shutter for such opening which may be readily and conveniently disposed for operation to serve either of these purposes and which may be adjusted to its working positions by manipulation of the endless operating cord 18 from the interior of the inclosure without the necessity of the operator getting outside the inclosure and without interference with or from 50 the screen material 19 in case such is used. It will also be seen that the invention provides a combined awning and shutter which may be inexpensively constructed and applied and which may be constructed in conventional sizes for 55

immediate application to any inclosure having an opening of any of the conventional sizes used. As stated, modifications falling within the scope of the invention as defined by the appended 5 claims may be made without departing from the spirit or sacrificing any of the advantages of the invention.

Having thus described the invention, what is claimed is:

10. 1. In a combination shutter and awning, the combination of sections hingedly connected together, means for supporting said sections, means for guiding opposite end portions of one of said sections, a guide pivotally connected with said section intermediate the ends thereof, and means connected with said guide for relatively moving said sections.
15. 2. In a combination shutter and awning, the combination of sections hinged together at adjacent edges, hinge means connected with one of said sections for supporting the same, means for guiding opposite end portions of another of said sections, a guide member hinged to the last-mentioned frame intermediate the ends thereof, a rod mounting said guide member for movement lengthwise thereof, and means connected with said guide member for relatively moving the sections.

3. In a combination shutter and awning, the combination of sections hinged together at adjacent edges, hinge means connected with one of said sections for supporting the same, means for guiding opposite end portions of another of 5 said sections, a guide member hinged to the last-mentioned frame intermediate the ends thereof, a central guide channel receiving said guide member for movement lengthwise thereof, and means connected with said guide member and 10 operable from a point within an enclosure for relatively moving the sections.

4. In a combination shutter and awning, the combination with an enclosure having an opening having upright tracks on opposite sides thereof, each of said tracks having an outwardly extending edge portion, of sections hinged together at adjacent edges, and hinge means connecting one of said sections with the enclosure, another of said sections having guide rollers arranged for 20 guiding movement on the edge portions of the tracks, and said sections having grooves in the inner faces thereof aligned with said rollers in positions to receive the edge portions of the tracks upon extension of the sections. 25

JOHN G. COX.
